ORTHOPEDIC APPLIANCE

Frederic F. Burchsted, Beverly, Mass.

Application January 6, 1942, Serial No. 425,755

7 Claims. (Cl. 5—92)

My invention relates to equipment useful in treating fractures of the arms or legs, disease of joints and the like. It comprises an improved universal splint support and improved splints with self-contained tensioning mechanisms.

The modern technique of treating fractures involves stretching or tensioning the fractured member so that the natural secretion resulting in new bone structure will flow in even distribution through the break and in order to maintain the separated bone members in proper alignment.

Considerable difficulty has been experienced in building splints which will not slip and permit the bones to go out of alignment or come together at an improper angle. Furthermore no splint heretofore in use has provided means for determining the amount of tension exerted on the fractured limb.

One object of my invention is to provide a universal splint support adapted to be clamped to a bed and making it possible to suspend a splint over any selected area of the bed and at any desired angle in order that the splint may be disposed in the fashion most effective and comfortable for the patient.

A further object of my invention is to provide a splint having self-contained tensioning mechanism including means for registering the amount of tension exerted on a fractured limb in order that the break in a limb may be held apart sufficiently to permit the bone-forming secretion to be evenly and efficiently distributed through the area of the fracture.

An important feature of my invention consists in an improved splint combining in a self-contained unit improved means for supporting a leg in bent position and means for exerting tension on the upper part of the leg, the pull being exerted in alignment with the bones of the upper leg.

Another feature of my invention resides in a construction whereby the splints maintain the fractured limb in proper condition without resort to outside connections or supports, with the result that the splint can be applied to the patient at the fracture reducing table and the patient thereafter transported to a bed to which the universal support of my invention has been applied.

Among the several advantages resulting from the practice of my invention are the saving in time of surgeons and attendants, greater comfort to the patient, less chance of maladjustment of the fractured limb, and the self-contained nature of the splint which allows the patient to be moved to or from his bed without affecting the condition of the fracture.

These and other objects and features of my invention will be more readily understood and appreciated from the following detailed description of a preferred embodiment thereof, selected for purposes of illustration as the best mode known to me by which my invention may be practised, and shown in the accompanying drawings, in which:

Fig. 1 is a view in perspective showing the universal splint support and four splints assembled with a bed.

Fig. 2 is a view in cross-section through the bridge member and carriage.

Fig. 3 is a view in front elevation of the adjustable splint hanger and hook.

Fig. 4 is a view in perspective showing a modified form of tensioning device for a leg splint.

Fig. 5 is a view in side elevation of a scale used to check slippage.

Fig. 6 is a view in perspective of a modified splint hanger.

Fig. 7 is a view in side elevation showing the joint between the hollow rods of a splint and the tensioning frame, and

Fig. 8 is a view in perspective of a splint-support for a wheel chair.

The illustrated embodiment of my invention is shown in Fig. 1 as assembled and mounted upon an iron hospital bed having the head board 10 and a foot board 11 and a mattress 12.

The main frame of the apparatus comprises an upright member 13 having an intermediate overhead track portion 14, and a second upright member 15 which has a reduced tongue welded to its forward end, telescopically and adjustably received within the end of the track portion 14 and adapted to be clamped in the proper position by longitudinal adjustment of winged set screws 16 which pass through cross bars in the track portion 14 and bear against a tongue which projects from the upright member 15. The upright members 13 and 15 are forked and are provided with any convenient form of clamping mechanism. That herein shown includes a cross bar shaped to rest on the bed rail and hooks that pass down through the cross bars and are provided with winged nuts by which they may be drawn into clamping engagement with the rail. The bridge member 15 which is secured to the foot of the bed is considerably longer than the bridge member 13 so that the intermediate track portion may be adjusted to a horizontal or level position. These members are all of angle iron construction, and in assembled condition constitute a light, stiff and strong bridge member extending

longitudinally over the patient and at a sufficient height above him to afford free access.

Upon the track portion of the frame are adjustably mounted a pair of similar carriages 17 and 30. The carriage 17 has two pair of truck rollers 18 running above the flange of the track member, and two pair of truck rollers 20 running below the flange of the track member. Flanges 24 on the rollers, as shown in Fig. 2, serve to guide the rollers along the track. Clamping bolts 19 are provided by which the carriage 17 may be located in any desired adjusted position upon the track 14, or if desired, the clamping bolts may be left loose and the carrier allowed to move freely in the track. A strut 21 extends transversely between the sides of the bridge member 13 serving to reinforce this member and also to serve as a stop to prevent the carriage 17 from running off the lower end of the track 14.

The carriage 17 may be removed bodily from the track 14 in the following manner. By loosening the wing nuts 19 the truck rollers 20 are dropped down until the flanges 24 clear the bottom of the track 14, thus allowing the shaft carrying the rollers to be turned at right angles to its normal position. After this has been accomplished, the carriage 17 may be lifted bodily and removed, the rollers 20 passing up between the sides of the track 14.

The carriage 17 extends transversely beyond the sides of the track 14. At each end it is provided with a downwardly extending clamping bolt 23, upon which is pivotally hung a double arm 22, that is to say, an arm comprising two spaced side members, and in the outer side of each is formed a track. From each of the arms 22 of the carriage 17 is suspended an arm splint. In Fig. 1 the connections between the arms 22 and this splint are omitted for the sake of clearness. The carriage 30, however, is similar in respect to the carriage 17. It is provided with downwardly extending bolts 35 from which are suspended the double arms 34, and from each of these arms a leg splint is suspended by mechanism which will now be described and which it will be understood may be similar to the corresponding suspension of the arm splints. It will be seen that each arm 22 is supported so that it may swing freely beneath the track 14. At each side of the arm 34 is mounted a hanger having a substantially triangular frame 36, and a pair of truck rollers 37 running on the tracks in the arm 34. The lower apex of each frame is formed as a rectangular socket member 39, and these members are connected by a transverse rod. A vertical bar 38 having teeth 40 in one edge slides in each of the socket members 39.

Journalized in the socket members 39 is a shaft 42 which carries two pawls 44 normally engaging a pair of teeth 40 on the bars 38. A lever 46 secured to the shaft 42, Fig. 3, is urged in one direction by a spring 48, forcing the pawls into firm contact with the teeth 40. The lever 46 may be moved by hand in the opposite direction to free the pawls from the teeth, thus permitting the bars 38 to be adjusted vertically. Bolted to the lower inturned ends of the bars 38 is a cross-piece 47 from which a hook 45 is pivotally suspended. Springs 43 surround the bolts securing the cross-piece 47 to the bars 38 to provide a spring-cushioned mounting for the cross-piece. The hook 45 is integral with a channel shaped flange 49 which, with the hook, forms a long narrow pocket.

From the foregoing description it will be ap-

parent that I have invented an overhead suspension system for splints, which is capable of unlimited adjustment. The carriages 17 and 30 may be fixed at any desired point longitudinally of the bed, and the pivotally mounted arms 34 make it possible to locate the supporting point of a splint anywhere over the bed. The longitudinal adjustment of the hangers along the arms 34, and the vertical adjustment of the bars 38 under the system are still more flexible and capable of treating fractures of adults or children in any point in either arm or leg. I will now describe preferred embodiments of the improved splints of my invention, although the use of the suspension system heretofore described is not limited to employment with the said improved splints of my invention.

Splint for lower leg fracture

- 20 The splint designated generally by the letter A is designed particularly for use with fractures at or below the knee. It comprises essentially two spaced hollow rods 50 connected at one end to a semi-circular ring 52 of steel covered with a cushioning material such as sponge rubber. At their other ends the rods 50 are secured to an arched cross member 54. A pair of leg-supporting slings 55 and 56 are supported between the rods 50 by straps encircling the rods, and each rod carries a strap 57 which straps pass around the leg of the patient to keep it properly aligned as it rests on the slings 55 and 56. An arched cover 51 is supported across the splint by legs 53 resting on the rods 50.
- 25 Fitting telescopically into the rods 50 are the ends of a heavy wire frame 58, and a set screw 59 permits the frame 58 to be set at a fixed position with relation to the rods 50, as shown in Fig. 7. Slidably mounted on the frame 58 is a foot support 60 which comprises a cross bar 61 and a rectangular upright portion 62 with loops 63 of webbing which encompass the foot to hold it firmly in position. The frame 58 also carries a sling 64 arranged to support the heel and ankle of the patient. A hook 65 is adjustably mounted in the end of the frame 58 and is threaded to receive an adjusting nut 66. A spring scale 8 is carried by the hook 65 and a hook secured to the cross bar 61.
- 30 When the splint A is to be used, the fracture is reduced and the splint is then placed under the leg so that it is supported on the slings 55, 56 and 64. The loops 51 and 53 are then applied to keep the leg in proper alignment. Then adhesive tape 67 is secured to the leg above the ankle and brought down to the cross bar 61 and secured thereto. The frame 58 is extended until the tension on the leg, as registered by the scale 8, approaches the desired value. The telescopic mounting of the frame 58 permits the splint to be adjusted to legs of various lengths. The set screws 59 are then turned up tight and stop blocks, which are slidably carried on the frame 58, are fixed in position adjacent the foot support 60 to prevent retrograde movement thereof. The nut 66 may be turned to apply a correction on the scale 8 on the cross bar 61, and thus through the adhesive tape 67 to the leg of the patient.
- 35 An arcuate arm 68 mounted on the frame 58 carries on its outer end an adjustable finger 69 upon which is mounted a horizontal scale 70; the scale 70 extends between the arms of a slotted upright member 71 which is taped to the patient's leg. When the splint has been applied to the

patient and the proper tension obtained, the location of one edge of the member 71 against the scale 70 is noted. The scale is useful to check slippage and also to show how much the limb is being stretched. Any resulting change of tension on the leg will be registered on the scale 70 so that the orthopedic surgeon in charge of the case can make an accurate readjustment later by manipulating the nut 66. Adjustable stop blocks 77 are provided behind each of the foot rest carriages 60 to safeguard excessive tension which might otherwise occur from movement of the patient.

As an alternative method of securing tension on the patient's leg, I contemplate the use of a Kirschner wire tractor, as suggested in Fig. 4. In this case the frame 58 is utilized as before, but a modified form of foot support is required. It includes a cross bar 72 slidably carried by the frame 58, an upright member 74 to carry aligning straps for the foot (not shown), and a V-shaped frame 76 having a downwardly extending lug 78 at its outer end. After a Kirschner wire 80 has been inserted in the os calcis of the fractured leg, it is gripped by a Kirschner wire tractor 82, of the type shown in U. S. Letters Patent No. 1,967,471. The wire tractor 82 is connected by a cord 84 to the lug 78, and tension may be adjusted by tightening or slackening the cord. Obviously other methods of skeletal traction may be accommodated by the frame 58.

Splint for upper leg fracture

The splint shown generally at B is particularly useful for the treatment of fractures above the knee. As in the splint A, the splint B comprises a pair of hollow rods 90 into which is telescopically fitted a frame 92; and a rubber covered semi-circle of steel 94 connects the other ends of the rods 90.

Also employed is an auxiliary frame 96 which has ends received in a pair of fittings 98 which secure the frame to the rods 90 and permit angular adjustment. The frame 96 provides a support for the uninjured lower leg, and is provided with a canvas sling 98, foot support 100 and loops or strap 102 which align the foot and leg as explained in the description of the splint A.

Slidably carried on the frame 92 is a cross bar 104, and safety stops 106 controlled by set screws are provided to limit movement in one direction of the bar 104 on the frame 92. A spring scale 108 is suspended between the bar 104 and an adjustable hook carried in the end of the frame 92. A stout cord 110 leads from the bar 104 to a Kirschner wire tractor 112 which grips the ends of a wire passed through the femur. A pair of straps 114 connect the ends of the frames 92 and 96 to limit relative angular movement thereof in one direction.

Fastened to one of the hollow rods 90 is an L-shaped arm 116 through the outer end of which is threaded a bolt 117; on the end of the bolt facing the patient's leg is a pressure disk 118 arranged to bear on the femur. After the tension on the patient's leg has been adjusted and the foot and leg properly aligned, the disk 118 is screwed in until it takes some pressure off the pelvis, bringing relief from discomfort caused by pressure of the ring 52 or 94 against the pelvis. The pressure exerted by the disk 118 may act counter to pressures exerted elsewhere or serve to distribute the pressure more evenly. A similar arrangement may be applied to splint A.

Splint for lower arm fracture

The splint C is designed particularly for use in the treatment of fractures of the lower arm and includes a pair of rods 120 connected to a ring 122 of steel covered with cushioning rubber and to an arcuate cross bar 124. The cross bar 124 is provided with a series of tapped holes into which may be threaded a bolt 126 carried by the hook 45. The suspension of the splints from the overhead frame is the same in all cases, the bolt 126 being optional. It will be obvious that by selecting a hole and tightening the bolt 126, the splint C may be made to hang at a predetermined angle. Carried by the telescoping rods 120 is a canvas strap 128 adapted to pass over the patient's arm.

A frame 130 comprising a pair of upright legs and a horizontal U-shaped portion is adjustably clamped to the rods 120 and is provided with a pair of clamps 132 which receive a vertical U-shaped frame 134. To keep the patient's arm in proper alignment I provide two straps 136 carried by the frame 134 and encircling the arm. A pulley or sheave 138 is journaled at the top of the frame 134, and a cord travels over the pulley, being connected at one end to a spreader bar 140 from which lead strips of adhesive tape 142 which are wound about the patient's wrist. The other end of the cord is connected to a spring scale 144 secured to a turnbuckle 146 which is in turn secured to the U-shaped portion of the frame 130. A hand grip 148 is secured to the upright portion of the frame 130 below the spreader bar 140.

After the fracture has been reduced and the lower arm immobilized the splint C is strapped in place with the arm at an angle. The adhesive tape 142 is applied to the arm and secured to the spreader bar 140. The set screws 132 are loosened and the frame 130 is raised until the desired height for the arm is reached, at which point the frame 130 is locked in position and the turnbuckle 146 is turned up until the scale 144 registers the tension desired. The strap 128 pulls against the arm above the elbow counter to the pull on the scale.

Splint for fractures of the upper arm

The splint designated by the character D is particularly useful for the treatment of upper arm fractures. This splint comprises a pair of hollow rods 150 connected at one end to a rubber-covered steel ring 152 and to an arcuate cross bar 154. A frame 156 of metal has ends sliding telescopically in the hollow rods 150 and adapted to be locked in position by means of set screws 158 at the base of the cross bar 154. Slidably mounted in the frame 156 is a cross-bar 160 adapted to be locked in fixed position by means of stop blocks 162. A spring scale 164 is suspended between the bar 160 and a hook 166 threaded through the end of the frame 156. A hand grip 168 is also connected to the bar 160. The rods 150 and the frame 156 support a pair of canvas slings 170. Adhesive tape 172 is wrapped around the patient's arm below the elbow and made fast to the bar 160.

After the upper arm fracture has been reduced, the adhesive tape 172 is applied, the position of the frame 156 is fixed, and the blocks 162 are positioned to force the bar 160 along the frame 156 until the scale 164 registers almost the tension desired. Then the hook 166 is adjusted to provide the exact tension required. The splint is then

slipped over the hook 45 which has previously been adjusted to the desired position. In order to counterweight the arm splints a pulley 180 may be connected to the bed frame, and a cord 182 connected at one end of the ring 152 runs through the pulley 180 and to a weight 184. The weight 184 is selected according to the amount of support desired.

In Fig. 6 I have shown an alternative form of hanger to take the place of the hanger 36. In the modified form the hanger comprises a pair of triangular supports 180 carrying truck rollers (not shown) adapted to fit on the tracks of the arms 34. A pair of vertical rods 182 slide freely in the members 180 and support a cross-bar 184 from which may be suspended a hook (not shown) to hold a splint. A shaft 186 is secured between the supports 180, and provides a mounting for a sheave 188. A weight 190 is suspended from a cord 192 which runs over the sheave 188 and is secured at its other end to the cross bar 184. After a splint has been secured to this modified form of hanger, additional weights may be placed on the weight 190 until the splint is properly counterbalanced. Thus the patient is relieved of the sensation of great weight and may move the injured limb slightly without discomfort. The cross bar 184 may be secured to the rods 182 by bolts 193 which slide in the cross bar 184, are threaded into lugs on the end of the rods, and are surrounded by springs 194, thus providing a yielding connection between the splint and the hanger.

In Fig. 8, I have illustrated a support adapted to fit on a wheel chair and designed to receive any of the splints heretofore described. The support comprises a single length of wire 200 bent to fit over the foot board 202 of a wheel chair and presenting lateral portions bounded by upright portions, in the rods of a splint may be received, as for example the rods 50 of the splint A. A splint may be detached from its hook 45 and then the patient can be placed in a wheel chair. All this can be accomplished without disturbing the alignment of, or tension upon, the fractured member, since the splints are self-contained units, maintaining tension and alignment without resort to outside assistance.

It will be understood that the arrangement and number of aligning straps or guides 57-63 may be varied at the discretion of the surgeon in the various cases under treatment. The apparatus, of course, can be used for a single fracture or injury, or for the treatment of both arms and both legs, being illustrated herein as working in that manner to show its full capacity.

In conclusion, some additional features of my invention may be referred to. For example, the parts of the splint are easily disassembled for cleaning and sterilization. Furthermore the universal splint support can be used simultaneously with a number of splints, while each splint is individually adjustable to accommodate the particular type of fracture involved. All of the parts of the splints and supporting frame are securely locked so that the bed may be moved about from place to place without harm to the patient.

Having thus described my invention what I claim as new and desire to secure by Letters Patent of the United States is:

1. A splint support which comprises a pair of adjustably connected bridge members adapted to be supported above a bed, a carriage slidably mounted on said bridge members, a pair of arms

5 pivotally connected to and suspended from said carriage, a track formed in the sides of each arm, hangers slidably mounted on said tracks, and a vertically adjustable hook suspended from each hanger.

2. A splint supporting structure, which comprises a pair of interlocking adjustably connected bridge members arranged to be secured to and above a bed, a carriage mounted on said bridge members for movement longitudinally thereof, means for immobilizing the carriage, a pair of arms suspended from said carriage and pivotally connected thereto, a hanger slidably mounted on each arm, a pair of bars secured to said hangers, means providing vertical adjustment of said bars, and a hook suspended from said bars.

3. A splint support which comprises a pair of bridge members, means for clamping said bridge members to the head and foot of a bed, an adjustable connection joining said bridge members, a track formed by said bridge members, a pair of carriages mounted on rollers disposed on said track, a pair of arms pivotally secured to each carriage and arranged to overhang a bed, a track formed in each arm, a hanger mounted on rollers disposed on each track, and a vertically adjustable connecting member carried by each hanger.

4. A splint support which comprises a cooperating pair of supporting members shaped to be detachably connected to the head and foot of a bed and having an adjustable track-carrying portion extending between their upper ends, and a carriage movable longitudinally upon said track-carrying portion, said carriage being provided with track-engaging elements and clamping means whereby the carriage may be clamped in any selected position on the track or disconnected and removed from the track, and having also a vertical pivot extending downwardly below said track-carrying portion and a splint-carrying arm freely movable about said pivot and beneath said track-carrying portion.

5. A splint supporting structure comprising a bridge arranged to be secured in position above a bed, a plurality of carriages mounted for independent movement longitudinally above the bed on said bridge, a pair of laterally adjustable arms on each carriage and a hanger supported from each arm and by the movement of the carriages and arms being adapted for universal adjustment above the bed.

6. Apparatus for hospital beds including a vertically adjustable bridge structure providing a longitudinal track above the bed, a carriage movable thereon, and extending transversely beyond the track on both sides thereof, a downwardly extending pivotal support at each side of the carriage, an arm on each support arranged to swing freely and independently beneath said track, and a splint support depending from each arm.

7. Apparatus for hospital beds including an overhead track, a carriage movable thereon, a support extending downwardly from the carriage to a point below the track, an arm pivotally mounted on the support and having spaced side walls, and a splint hanger comprising triangular frames suspended in spaced relation from the walls of said arm and connected together at a point below the arm.
